(Cl. D52—3)

To all whom it may concern:

Be it known that I, Hans G. Nissen, a citizen of the United States, residing in New York, county of New York, and State of New York, have invented a new, original, and ornamental Design for a Vending Machine Cabinet or Similar Article, of which the following is a specification, reference being had to the accompanying drawing, forming a part thereof.

The figure is a front perspective view of a vending machine cabinet or similar article showing my new design.

The opposite side of the vending machine cabinet or similar article is substantially the same as the side disclosed. The back is substantially plain.

I claim:

The ornamental design for a vending machine cabinet or similar article, substantially as shown and described.

HANS G. NISSEN.
